SHOE

Max Liberman, Brooklyn, N. Y.

Application October 13, 1933, Serial No. 693,415

6 Claims. (Cl. 36—71)

This invention relates to new and useful improvements in ladies' shoes and has more particular reference to the type of shoes known as opera pumps, and similar shoes.

Quite often the upper edge of the vamp of a lady's shoe irritates the foot and causes discomfort. Numerous attempts have been made to overcome this effect by placing sponge rubber pads or other pads in the vamp portion of the shoe spaced in from the binding edge. Such construction is highly unsatisfactory since it is the binding edge which causes all the trouble.

This invention has for an object the construction of the binding edge of the vamp portion of the shoe in such a manner that it is exceptionally resilient and thus overcomes the undesirable feature previously pointed out.

Still further the invention particularly proposes the provision of a small resilient pad, preferably of soft sponge rubber, for location in the vicinity of the upper portion of the vamp of a shoe against the inner sides of the vamp leather and lining and arranged with its edge flush with the edge of the vamp so as to render this edge of exceptionally resilient nature.

Still further the invention proposes the provision of a binding over the flushed edges of the pad and the vamp of the shoe.

As another object of this invention it is particularly proposed to provide a line of stitches spaced in slightly below the edges of the pad and the vamp for the purpose of holding the pad in fixed position without subtracting from the resilient quality pointed out.

Still further this invention also contemplates the formation of the edge of the resilient pad in a manner so that it extends over and actually covers the edge of the vamp, and furthermore is adapted to be located below the binding at the upper edge of the vamp.

Still further the invention proposes the construction of a shoe as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a shoe constructed according to this invention.

Fig. 2 is a fragmentary enlarged sectional view taken on the line 2—2 of Fig. 1.

Fig. 3 is an elevational view of the pad used in Figs. 1 and 2.

Fig. 4 is a view similar to Fig. 2 but illustrating a modified construction.

This invention is applied to a lady's shoe 10 having a vamp portion 11 terminating at the top in a binding edge 12. The invention comprises the provision and location of a small resilient pad 13 located in the vicinity of the upper edge of the vamp and against the under side of the vamp leather or other material and having an edge 14 flush with the edge 15 of the vamp 11 at the binding 12.

The vamp 11 is shown provided with a lining 16 which itself does not form an important part of this invention though customarily the leathers of the vamps of shoes are provided with such linings. The resilient pad 10 is disposed immediately below the lining 16. The edge 17 of the pad 13 is chamfered as clearly illustrated in Figs. 2 and 3 so that the thickness gradually meets the vamp without producing a sudden drop which would form a shoulder capable of irritating the foot. A small soft binding strip 17', preferably of very soft leather is arranged below the pad 13 along the edge thereof and is merely for the purpose of providing a reinforcement so that the pad 13 may be secured in place as hereinafter more specifically described.

The pad 13 is fixed in place by a line of stitches 18 extending a slight distance below the edges 14 and 15. This line of stitches 18 secures the binding strip 17, the pad 13, the vamp 11 and one edge of the binding 12 together. The binding 12 has a portion disposed outside of the vamp portion 11 and then is bent over to extend and cover the edges 14 and 15. The shoe is provided with a lining which is secured by a line of stitches 19 upon the inner edge of the binding 12. This lining comprises a leather portion 20 and a cloth portion 21. The leather portion 20 extends from the back of the shoe along the sides and narrows out immediately below the edge of the vamp.

It is important that the leather 20 be of one piece at the vamp so as not to produce seams which are liable to hurt the foot. The leather portion 20 is shown extending completely to the rear of the shoe and there having adjacent edges 22 in edge alignment with each other. A small pad may be used to cover the exposed edges 22 as it is customary practice. The cloth portion 21 of the lining is stitched

to the leather portion 20 and extends below the vamp portion of the shoe.

It is a feature of this invention that the edge 14 of the pad 13 is flush with the edge 15 of the vamp portion and also with the edge of the binding strip 17'. Since the pad 13 extends to the edge of the binding the edge of the vamp portion will be highly resilient. The invention would be defeated if the pad 13 were located below the edge 15 so that the binding 12 extended over the edge 15 and perhaps the binding strip 17'. In this case there would be no resilience for the edge of the vamp and the binding would be capable of rubbing against the foot. In prior shoe constructions it is customary to make the edge of the vamp of sufficient thickness by necessary layers of material so that the shoe maintains its shape, and I am aware of the fact that several attempts were made to place pads within the vamp but spaced from the binding edge, and such constructions have been proved highly unsatisfactory.

In Fig. 4 a modified form of the invention has been disclosed in which the pad 13' is formed with an enlarged edge 23 extending over the edge 15 of the vamp and the edge of the binding strip 17'. The binding strip 12 extends over the enlarged portion 23 and so the binding of the vamp portion of the shoe is directly cushioned by the enlarged portion 23 of the pad 13'. In other respects this form of the invention is identical to the previous form and corresponding parts may be recognized by the same reference numerals. The enlarged portion 23 may be formed upon the edge of the pad 13 for molding, or the enlarged portion 23 may be produced merely by extending the edge of the pad past the edge 15 of the binding and arranging the binding 12 over the edge of the pad so as to compress the edge into an enlarged portion.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

1. In a shoe, a vamp with a binding edge, a small resilient pad, located in the vicinity of the upper portion of said vamp against the inner side of the vamp and having a full sized edge flush with the said binding edge, and a binding over said edges, said resilient pad being

held in place with a line of stitches slightly below said edges so that the said full sized edge of the pad is free.

2. In a shoe, a vamp with a binding edge, a small resilient pad located in the vicinity of the upper portion of said vamp against the inner side of the vamp and having a full sized edge flush with the said binding edge, a binding over said edges, said resilient pad being held in place with a line of stitches slightly below said edges so that the said full sized edge of the pad is free, and a binding strip extending along the under side of said pad and having an edge flush with the edge of said pad and also engaged by said line of stitches.

3. In a shoe, a vamp with a binding edge, a small resilient pad located in the vicinity of the upper portion of said vamp against the inner side of the vamp and having a full sized edge flush with the said binding edge, and a binding over said edges, said resilient pad being held in place with a line of stitches slightly below said edges so that the said full sized edge of the pad is free, the outer edge of said binding being bent under itself and having its edge flush with said edges and secured down by said line of stitches.

4. In a shoe, a vamp with a binding edge, a small resilient pad located in the vicinity of the upper edge of said vamp against the inner side of the vamp and having an enlarged top edge extending over the binding edge of said vamp, and a binding over the enlarged edge of said pad.

5. In a shoe, a vamp with a binding edge, a small resilient pad located in the vicinity of the upper edge of said vamp against the inner side of the vamp and having an enlarged top edge extending over the binding edge of said vamp, a binding over the enlarged edge of said pad, and a line of stitches slightly spaced below said binding edge and securing an inturned edge of said binding, said vamp and said resilient pad together.

6. In a shoe, a vamp with a binding edge, a small resilient pad located in the vicinity of the upper edge of said vamp against the inner side of the vamp and having an enlarged top edge extending over the binding edge of said vamp, a binding over the enlarged edge of said pad, and a line of stitches slightly spaced below said binding edge and securing an inturned edge of said binding, said vamp and said resilient pad together, and another binding strip on the under side of said pad beneath said enlarged edge of the pad and also held in place by said line of stitches.
